UNITED STATES PATENT OFFICE.

PAUL SEMANCIK, OF MAYNARD, OHIO.

RAILWAY-TIE AND RAIL-FASTENER.

1,250,366.

Specification of Letters Patent. Patented Dec. 18, 1917.

Application filed October 13, 1917. Serial No. 196,394.

To all whom it may concern:

Be it known that I, PAUL SEMANCIK, subject of the King of Hungary, residing at Maynard, in the county of Belmont and State of Ohio, have invented certain new and useful Improvements in Railway-Ties and Rail-Fasteners, of which the following is a specification.

This invention relates to certain new and useful improvements in railway ties and rail fasteners.

The primary object of the invention is the provision of a strong and efficient tie adapted for the locking reception of railway rails in their operative positions thereon without the employment of any bolts, screws or other similar hold-fast devices which are now in common use.

A further object of the invention is the provision of a metallic railway tie formed in two identical parts permitting the device to be cheaply manufactured for commercial use, the arrangement being such that the device may be readily assembled in supporting relations beneath the rails of a railroad line and then securely locked upon the rails against accidental displacement although readily releasable by railroad employees.

A still further object of the invention is the provision of a two-part tie having complementally arranged portions readily receiving the rails of a track and accurately positioning the same according to the desired gage of the road, the tie being readily disengaged and removed from the rails as well as attached thereto at will and affording broad abutments for the rails as well as having a disengageable attachment with the rails prior to the final locking operation of the device.

With these general objects in view and others that will appear as the nature of the invention is better understood, the same consists in the novel combination and arrangement of parts hereinafter fully described, illustrated in the accompanying drawing and then claimed.

In the drawing forming a part of this application and in which like designating characters refer to corresponding parts throughout the several views,

Figure 1 is a side elevation of an assembled tie of my construction with parts broken away and with railway rails operatively mounted thereon.

Fig. 2 is a top plan view thereof.

Fig. 3 is a top plan view of the tie with the sections thereof slightly separated.

Fig. 4 is a perspective view of one of the tie sections and

Fig. 5 is a perspective view of the locking wedge employed with the device.

It being understood that the device is adapted for operatively positioning railroad rails upon the road bed, the device is herein illustrated in connection with rails 10 positioned in locked arrangement accurately positioned the proper distance apart by means of two identically formed sections 11 and 12, which constitute in connection with a locking wedge 13, my complete device or tie structure.

The tie sections 11 and 12 being identical in form with relatively wide and narrow portions or halves 14 and 15 are adapted to be oppositely positioned with their inner sides flatly contacting each other when the tie is assembled. The narrow end 15 of each tie is provided with a transverse block 16, substantially rhomboidal in cross section projecting above the upper face 17 of the tie with its inner longitudinal edge 18 overlying the tie spaced therefrom and adapted to overlie the adjacent base flange 19 of one of the rails 10.

The forming of the tie sections with different sized halves provides a cut-away portion 20 substantially equal to one-quarter of the dimensions of the tie section and providing a shoulder 21 at the inner end of the larger half 14 of the section, adjacent the cut-away portion 20 thereof. The block 16 projects substantially across the cut-away portion 20 of the carrying section and is adapted for sliding reception within a correspondingly formed dove-tail groove 22 in the adjacently positioned enlarged half 14 of the companion tie section. An abutment 23 is arranged upon each half 14 of the tie sections traversing the entire width thereof and arranged spaced inwardly of the grooves 22, it being understood that the abutments 23 project above the top 11 of the tie substantially the same distance as and being similar in form to the aforementioned blocks 16.

An inwardly extending pin 24 in the form of a dowel is carried upon the half 15 of each tie section adapted for reception within a receiving socket 25 correspondingly positioned within the inner face of the larger half 14 of the adjacent section. It will be understood that the rails 10 are

RAILWAY TIE KEEPER AND TIE-UP SYSTEM

first arranged with one of the sections 11 or 12 engaging the bottom flanges thereof by means of the block 16 and the abutment 23 of such section, which thereby accurately 5 positions the rails 10 the proper distance apart. The companion tie section is then positioned with its block and abutment upon the opposite flanges of the rails which are not engaged by the other section and the 10 sections are slidably moved toward and into engagement with each other. The pins 24 will then be seated within the socket 25 and the block 16 will be arranged within the 15 grooves 22 with the inner faces of the sections flatly contacting each other and with the shoulders 21 of the sections in substantial contact. The wedge 13 is then driven into tapered notches 26 in the shoulders 21 and this action moves the tie sections 11 and 12 longitudinally and in opposite directions, whereby the block 16 of each section 20 is forcibly drawn toward the abutment 23 of the companion section, the sections 11 and 12 being thereby secured in their tie formation 25 and locked upon the rails.

It will be noted that while the block 16 may slide a short distance within the grooves 22 longitudinally of the tie, under the influence of the wedge 13, still, the engagement 30 between the block 16 and grooves 22 is such as to prevent the tie sections 11 and 12 from dropping off of the rails 10 when the wedge 13 is removed, the pins 24 and sockets 25 preventing relative vertical swinging movement of the tie sections.

A serviceable and strong tie is provided that may be easily manufactured and as the sections thereof being identical, only one form of section is necessary and the sections 40 may be readily assembled upon the rails without any tools but are readily locked in position thereon in their tie formation for permanent arrangement upon the road bed although the tie may be disassembled at will. The form of the invention herein 45 shown is believed to be preferable although

minor changes may be made therein without departing from the spirit and scope of the invention as claimed.

What I claim as new is:—

1. A railway tie comprising identical sections having relatively wide and narrow halves, the wider halves having dove-tail grooves in their upper faces, transverse abutments upon said wider halves adjacent 50 said grooves, transverse blocks carried by and projecting above and inwardly of the narrower halves adapted for sliding reception within said grooves when the sections are laterally moved into contact with each other with the said blocks and abutments arranged upon the base flanges of rails, dowel pin connections between said sections adapted for preventing relative vertical swinging movement therebetween and a 55 locking wedge for the said sections.

2. In combination with railway rails, a tie associated therewith comprising identically formed sections having complementally arranged wide and narrow end portions 70 forming a substantially central squared shoulder upon each section with a notch in each shoulder, transverse blocks carried by the narrow end sections substantially rhomboidal in cross section and having tapered 75 inner edges above the face of the section adapted for overlying the outer base flanges of the rails, similarly shaped abutments upon said wider end portions adapted for overlying the inner base flanges of the rails 80 when operatively arranged, the wider end portions having dove-tail grooves adapted for the reception of said blocks when the sections are positioned in contact with each other upon the rails, dowel pin connections 85 between said tie sections outwardly of said blocks and grooves and a locking wedge arranged within said notches when the tie is locked upon the rails.

In testimony whereof I affix my signature. 90

PAUL SEMANCIK.

Copies of this patent may be obtained for five cents each, by addressing the "Commissioner of Patents, Washington, D. C."
